UNITED STATES PATENT OFFICE.

JOSEPH CONNER, OF NEW YORK, N. Y., ASSIGNOR TO THE FIRM OF JOHN MATTHEWS, OF SAME PLACE.

SODA-WATER APPARATUS.

SPECIFICATION forming part of Letters Patent No. 404,172, dated May 28, 1889.

Application filed March 2, 1889. Serial No. 301,737. (No model.)

To all whom it may concern:

Be it known that I, JOSEPH CONNER, a resident of the city, county, and State of New York, have invented an Improved Soda-Water Apparatus, of which the following is a specification.

My invention relates, particularly, to the opening and closing of the delivery of the sirup-tank by certain devices which enable the rod or valve within the sirup-tank to be raised and lowered by a parallel rod within or an arm entering through the wall of the apparatus from without, or other device outside of the sirup-tank, and so arranged that the sirup-tank can be removed from the apparatus for the purpose of cleaning and filling without having to disconnect any parts or adjustments.

The object of my invention is to overcome certain objectional features of adjustments now existing as relates to the removal of sirup-tanks and the replacing of the same in apparatus now in common use.

The invention consists in the details of improvement and the combinations of parts, that will be more fully hereinafter set forth.

Reference is to be had to the accompanying drawings, forming part of this specification, in which—

Figure 1 is a vertical cross-section of the front portion of a soda-water apparatus, showing my improvements connected with the sirup-tank. Fig. 2 is an enlarged detail view of the under side of my improved valve-rod connection; and Fig. 3 is a longitudinal section on the line *c c*, Fig. 2.

The letter *A* in the accompanying drawings represents a portion of the casing of a soda-water-dispensing apparatus. *B* is the cover thereof, and *D* is the compartment in which the sirup-tank *E* is placed.

a is a sirup-measuring compartment at the lower part of the sirup-tank *E*, within which compartment is a valve, *b*, that is connected with a vertical rod or stem, *F*, that passes through the sirup-tank.

The above parts may all be of the ordinary or suitable construction, and form no part of my present invention.

The upper end of the rod or stem *F* is screw-threaded at *d*, and to connect most conveniently with an arm, *G*, that is carried by the rod *F*. The arm *G*, on its under side, is provided with a recess, *f*, (see Figs. 2 and 3,) which receives the end of a vertical rod or pusher, *H*. This rod or pusher is either angular, as in full lines, Fig. 1, extending through the front wall, *j*, of the case *A*, and provided with a knob, *l*, or it extends down, as by dotted lines, through guide-brackets *g*, in which case it may have a collar, *h*, having a set-screw, *i*, that is adapted to hold the collar in position. The collar *h*, coming against a bracket, *g*, holds the rod *H* in the proper position, with its upper end in the recess *f*. If the rod *H* projects through the side of the casing, a label may be placed upon it to designate the kind of sirup within its respective tank.

It will be understood that any desired number of tanks *E* may be placed in the apparatus, each one having a set of valve-actuating means above described.

By the above construction the sirup-tank can be removed from the apparatus for the purpose of cleaning and filling without having to disconnect any parts or adjustments, whereby much time and trouble are saved.

Having now described my invention, what I claim is—

The sirup-tank *E* and valve-rod *F*, having the projecting arm *G*, said arm having a recess on its under side, in combination with the pusher-rod *H*, engaging said recess, all arranged to admit the removal of the sirup-tank without disturbing the rod *H*, substantially as described.

JOSEPH CONNER.
